BENZOCARBAZOLONES

Stephen Sallay, Wynnewood, Pa., assignor to American Home Products Corporation, New York, N.Y., a corporation of Delaware
No Drawing. Filed Mar. 23, 1964, Ser. No. 354,149
9 Claims. (Cl. 260—315)

This invention relates to benzocarbazolones and more particularly to substituted hexahydrobenzocarbazol-5-ones and to the method by which these new compounds are prepared.

The new compounds of this invention include those encompassed within the following structure:

I

wherein R¹ and R² are selected from the group consisting of hydrogen, lower alkyl and lower alkoxy and R¹ and R² taken together are —O—CH₂—O—; R³ is selected from the group consisting of hydrogen, lower alkyl and lower alkoxy; R⁴ is selected from the group consisting of hydrogen, lower alkyl and benzyl and X is selected from the group consisting of =O and =N—NH₂. As used herein, lower alkyl is intended to include straight or branched hydrocarbons having 5 or less carbon atoms.

The new compounds of the present invention are prepared according to the following reaction sequence which while directed to the preparation of a single compound encompassed within those defined by Formula I represents the reaction by which other compounds falling within the class defined by Formula I are prepared.

To prepare the new compounds of the present invention, a hexahydro-1,4-naphthoquinone II is reacted with phenylhydrazine III by refluxing the reactants in the presence of an inert solvent for a period of from about 10 minutes to about 2 hours. The resulting intermediate IV, a naphthoquinone-1-phenylhydrazone, is then cyclized as shown to yield the desired product V, a benzo(a) carbazol-5-one.

The starting materials shown are known to those skilled in the art or are prepared by known methods. This is particularly so with the phenylhydrazine III and substituted derivatives of the same. The starting 1,4-naphthoquinone derivative represented by II, the latter being specifically 2,3,4a,5,8,8a-hexahydro-1,4-naphthoquinone are prepared according to the method of O. Diels and K. Alder, Ber.,

2

62, 2337, 1929. It is of course understood that the starting naphthoquinone II will be suitably substituted as by R³ (see Formula I) to provide the final product IV with such a substituent. As shown in Formula I, R³ is present in the starting naphthoquinone at the 8 (or 5, depending on nomenclature) position which is equivalent to the 4 position of the final product I. The R³ substituents which may be present on starting compound II, when R³ is other than hydrogen, are those previously defined with respect to Formula I and more specifically identified hereinafter.

The phenylhydrazine (III) reacted with the starting naphthoquinone II is well known in the art. The phenylhydrazine is substituted at the 3 and 4 positions when R¹ and R² are other than hydrogen, to provide the final product with the R¹ and R² substituents, as specified, at the 8 and 9 positions of the final product I.

In order to obtain the final products encompassed within Formula I, wherein R⁴ represents a substituent other than hydrogen, it is necessary to further react a compound of the type shown at V, i.e. wherein there is a hydrogen atom at the 11 position, with a suitable reagent. Such a reaction is carried out with the compound V, or derivatives thereof with sodium hydride or sodium amide in a selected, inert solvent such as dimethylformamide, toluene or the like followed by reaction with alkyl halide or a halide derivative, such as a benzyl halide including the substituted derivatives thereof.

Having obtained the final products represented by V, in the reaction sequence shown, further reaction of such a product (V) with hydrazine hydrate results in the product represented by VI. It will be noted that the latter represent those compounds wherein the X substituent of Formula I is =N—NH₂.

This reaction is carried out by suspending the benzo(a) carbazol-5-one (V) in an inert solvent and refluxing the reaction mixture for a period of from 10 minutes to about 1 hour. On cooling the desired product crystallizes out and is recovered in a conventional manner, yielding the desired hydrazone VI.

The new compounds of the present invention encompassed within those defined by Formula I have valuable properties which make them useful for pharmacological purposes. More specifically, the new compounds of the present invention are useful as blood pressure reducing or depressing agents.

When used as blood pressure depressants, the new compounds of this invention may be administered alone or in combination with pharmaceutically acceptable carriers, the proportion of which is determined by the solubility and chemical nature of the compound, chosen route of administration and standard pharmaceutical practice. They may be administered orally in the form of tablets or capsules containing such excipients as starch and milk sugar. They may be administered in the form of lozenges in which the active ingredient is mixed with sugar, corn syrups, flavoring agents and dyes. They may be administered orally in the form of solutions which may contain coloring and flavoring agents. They may also be injected parenterally.

The dosage of the present therapeutic agents which will be most suitable will vary with the form of administration and the particular compound chosen, and will also vary with the particular patient under treatment. Treatment will be started with small dosages substantially less than the optimum dose of the compound and increase the dosage by small increments until the optimum effect under the circumstances is reached. It will generally be found that when the composition is administered orally, larger quantities of the agent will be required to produce the same effect as a smaller quantity given parenterally. The compounds are useful in the same manner as other agents having a similar function and the dosage level is of the same

order of magnitude as is generally employed with these other therapeutic agents. The therapeutic dosage may be from 10 to 500 milligrams per day and may be administered in several different dosage units. Tablets containing from 25 to 250 mg. of active agent are particularly useful.

These new compounds (X=O) are also useful in the preparation of the new compounds disclosed in my co-pending application Serial No. 354,092, filed Mar. 23, 1964, relating to 5-aminobenzocarbazoles, now U.S. Patent No. 3,274,188, issued Sept. 20, 1966.

Reference now to the specific examples which follow will provide a better understanding of the new compounds of the present invention as well as the novel method by which these new compounds are prepared.

Example I

2,3,4a,5,8,8a - hexahydro-1,4-naphthoquinone (II) (O. Diels and K. Alder, Ber., 62, 2337, 1929) (16.4 g.) is covered with 200 ml. of methanol and refluxed with 10.0 g. of phenylhydrazine for twenty minutes. After cooling, crystals separate out, M.P. 164-166° C. The crude product, 2,3,4a,5,8,8a-hexahydro-1,4-naphthoquinone 1-phenylhydrazone (IV), is recrystallized from ethanol; M.P. 170-172° C. IR spectrum exhibited absorption at 5.85 μ (oxo).

1-phenylhydrazone derivative IV (52.0 g.) is dissolved in 470 ml. of acetic acid which is previously saturated with dry hydrochloric acid at room temperature. The temperature of the red colored reaction mixture rises up to 55° C. within two-three minutes and ammonium chloride separation begins. After fifteen minutes the reaction mixture is cooled and poured onto alkaline ice water. A white crystalline precipitate separates out, 36.0 g. (82%). The crude material recrystallized from methanol affords shiny needles, 1,4,4a,5,6,11b - hexahydro-11H-benzo(a) carbazol-5-one (V), M.P. 192-193° C. IR spectrum possesses the expected bonds at 2.90 μ (NH), and 5.84 μ (oxo). U.V. spectrum had the indole maxima at 224, 280, and 291 m μ .

Example II

Following the procedure of Example I, 5-methyl-2,3,4a,5,8,8a-hexahydro-1,4-naphthoquinone is reacted with 3,4-dimethylphenylhydrazine with the resulting product being cyclized with acid to yield 4,8,9-trimethyl-1,4,4a,5,6,11b-hexahydro-11H-benzo(a)carbazole-5-one.

Example III

According to the procedure of Example I, 5-methoxy-2,3,4a,5,8,8a-hexahydro-1,4-naphthoquinone is reacted with p-methoxyphenylhydrazine with the resulting product being acidified to yield 4,8-dimethoxy-1,4,4a,5,6,11b-hexahydro-11H-benzo(a)carbazol-5-one.

Example IV

Following the procedure of previous examples, 5-propyl-2,3,4a,5,8,8a-hexahydro-1,4-naphthoquinone is reacted with 3,4-dimethoxy-phenylhydrazine and the resulting product acidified to yield 8,9-dimethoxy-4-propyl-1,4,4a,5,6,11b-hexahydro-11H-benzo(a)carbazol-5-one.

Example V

According to the method of Example I, 5-ethoxy-2,3,4a,5,8,8a-hexahydro-1,4-naphthoquinone is reacted with 3,4-methylene-dioxyphenylhydrazine and the resulting intermediate product cyclized with dilute acid to produce 8,9 - methylenedioxy-4-ethoxy-1,4,4a,5,6,11b-hexahydro-11H-benzo(a)carbazole-5-one.

Example VI

Reacting 5 - methyl - 2,3,4a,5,8,8a-hexahydro-1,4-naphthoquinone with p-butyl-phenylhydrazine results in an intermediate product which on being cyclized yields 8-butyl-4 - methyl - 1,4,4a,5,6,11b - hexahydro-11H-benzo(a)carbazol-5-one.

Example VII

According to the method previously described, 4-ethyl-1,4,4a,5,6,11b-hexahydro-11H-benzo(a) carbazol-5-one is obtained by reacting 5-ethyl-2,3,4a,5,8,8a-hexahydro-1,4-naphthoquinone with phenylhydrazine and cyclizing the resulting product by acid treating.

Example VIII

Following the procedure previously described, reacting 5-ethyl-2,3,4a,5,8,8a-hexahydro-1,4-naphthoquinone with 3 - ethyl - 4 - methylphenylhydrazine produces a product which on acid treatment yields 4,9-diethyl-8-methyl-1,4,4a,5,6,11b-hexahydro-11H-benzo(a)carbazol-5-one.

Example IX

Reacting the product of Example I with sodium hydride in dimethylformamide followed by reaction with ethyl chloride results in 11-ethyl-1,4,4a,5,6,11b-hexahydro-11H-benzo(a)carbazol-5-one.

Example X

Reacting the product of Example I with benzylbromide according to the method described in Example IX results in 11 - benzyl-1,4,4a,5,6,11b-hexahydro-11H-benzo(a)carbazol-5-one.

Example XI

Reacting the product of Example I with butylbromide according to the method of Example IX results in 11- butyl - 1,4,4a,5,6,11b - hexahydro - 11H - benzo(a)carbazol-5-one.

Example XII

Reacting the product of Example II with benzylbromide according to the method of Example IX, there is obtained 11-benzyl-4,8,9-trimethyl-1,4,4a,5,6,11b-hexahydro-11H-benzo(a)carbazol-5-one.

Example XIII

40 Reacting the product of Example III with propylchloride according to the method of Example IX, one obtains 4,8 - dimethoxy - 11 - propyl - 1,4,4a,5,6,11b - hexahydro-11H-benzo(a)carbazol-5-one.

Example XIV

45 Reacting the product of Example IV with benzylbromide according to the method of Example IX, there is produced 11 - benzyl - 8,9 - dimethoxy - 4 - propyl - 1,4,4a,5,6,11b-hexahydro-11H-benzo(a)carbazol-5-one.

Example XV

50 Reacting the product of Example VII with benzylbromide according to the method of Example IX, one obtains 11-benzyl-4-ethyl-1,4,4a,5,6,11b-hexahydro-11H-benzo(a)carbazol-5-one.

Example XVI

To obtain 11-benzyl-8,9-dimethoxy-4-ethyl-1,4,4a,5,6,11b-hexahydro-11H-benzo(a)carbazol-5-one, one reacts 60 benzylbromide with 8,9-dimethoxy-4-ethyl-1,4,4a,5,6,11b-hexahydro-11H-benzo(a)carbazol-5-one according to the method of previous examples.

Example XVII

65 To obtain 4,8,11-triethyl-1,4,4a,5,6,11b - hexahydro-11H-benzo(a)carbazol-5-one, ethylchloride is reacted with 4,8 - diethyl - 1,4,4a,5,6,11b - hexahydro - 11H - benzo(a)carbazol-5-one according to the method of previous examples.

Example XVIII

To prepare 4 - ethyl - 1,4,4a,5,6,11b-hexahydro-11H-benzo(a)carbazol-5-one, 5-ethyl-2,3,4a,5,8,8a-hexahydro-1,4-naphthoquinone is reacted with phenylhydrazine 75 according to the method of Example I.

5

Example XIX

Reacting the product of Example XVIII with benzyl-bromide according to the method of Example IX, there is produced 4-ethyl-11-benzyl-1,4,4a,5,6,11b-hexahydro-11H-benzo(a)carbazol-5-one.

Example XX

1,4,4a,5,6,11b - hexahydro - 11H - benzo(a)carbazol-5-one (V) suspended in 50 ml. of hot ethanol and 2 ml. of hydrazine hydrate (98%) is added at once. The reaction mixture is refluxed for ten minutes. Upon cooling, 10 crystals of 1,4,4a,5,6,11b-hexahydro-11H-benzo(a)carbazol-5-one, hydrazone (VI) separate out, (6.7 g.) having a M.P. of 198-200° C.

Example XXI

Following the method of Example XX, 4-methyl-1,4,4a,5,6,11b-hexahydro-11H-benzo(a)carbazol-5-one is reacted with hydrazine hydrate to yield 4-methyl-1,4,4a,5,6,11b - hexahydro - 11H - benzo(a)carbazol - 5 - one, hydrazone. 15 20

Example XXII

According to the method of Example XX, 4-ethyl-11-benzyl - 1,4,4a,5,6,11b - hexahydro - 11H - benzo(a)carbazol-5-one, hydrazone is prepared by reacting 4-ethyl-11-benzyl - 1,4,4a,5,6,11b - hexahydro - 11H - benzo(a)carbazol-5-one with hydrazine hydrate.

Example XXIII

To prepare 4-methyl-8,9-dimethoxy-11-benzyl-1,4,4a,5,6,11b - hexahydro - 11H - benzo(a)carbazol - 5 - one, hydrazone, 4 - methyl - 8,9 - dimethoxy - 11 - benzyl - 1,4,4a,5,6,11b - hexahydro - 11H - benzo(a)carbazol-5-one is reacted with hydrazine hydrate according to the method of Example XX. 30

Example XXIV

To prepare 11-benzyl-1,4,4a,5,6,11b-hexahydro-11H-benzo(a)carbazol-5-one, hydrazone, 11-benzyl-1,4,4a,5,6,11b-hexahydro-11H-benzo(a)carbazol-5-one is reacted with hydrazine hydrate according to the method of Example XX. 35

Example XXV

Following the method of Example XX, 8,9-dimethyl-4-ethyl - 1,4,4a,5,6,11b - hexahydro - 11H - benzo(a)carbazol-5-one is reacted with hydrazine hydrate to prepare 45 50 8,9 - dimethyl - 4 - ethyl - 1,4,4a,5,6,11b - hexahydro-11H-benzo(a)carbazol-5-one, hydrazone.

Example XXVI

Following the method of previous examples, 4,8,11-trimethyl - 1,4,4a,5,6,11b - hexahydro - 11H - benzo(a)carbazol-5-one is reacted with hydrazine hydrate to prepare 4,8,11 - trimethyl - 1,4,4a,5,6,11b - hexahydro - 11H-benzo(a)carbazol-5-one, hydrazone. 55

6

Example XXVII

According to the method of previous examples, hydrazine hydrate is refluxed with 11-benzyl-8-propyl-1,4,4a,5,6,11b-hexahydro-11H-benzo(a)carbazol-5-one to produce 5 11 - benzyl - 8 - propyl - 1,4,4a,5,6,11b - hexahydro - 11H-benzo(a)carbazol-5-one, hydrazone.

While the present invention has been described with some degree of particularity, it is to be understood that such description is not intended in any manner to be construed as a limitation on the scope of invention. The invention is to be limited only by the claims appended hereto.

The invention claimed is:

1. A compound having the formula:

wherein R¹ and R² are selected from the group consisting of hydrogen, lower alkyl and lower alkoxy and R¹ and R² taken together are —O—CH₂—O—; R³ is selected from the group consisting of hydrogen, lower alkyl and lower alkoxy; R⁴ is selected from the group consisting of hydrogen, lower alkyl and benzyl; and X is selected from the group consisting of ==O and ==N—NH₂.

2. 1,4,4a,5,6,11b - hexahydro - 11H - benzo(a)carbazol-5-one.
3. 11 - lower alkyl - 1,4,4a,5,6,11b - hexahydro - 11H-benzo(a)carbazol-5-one.
4. 11 - ethyl - 1,4,4a,5,6,11b - hexahydro - 11H - benzo(a)carbazol-5-one.
5. 11 - benzyl - 1,4,4a,5,6,11b - hexahydro - 11H-benzo(a)carbazol-5-one.
6. 4 - ethyl - 11 - benzyl - 1,4,4a,5,6,11b - hexahydro-11H-benzo(a)carbazol-5-one.
7. 4,8 - dimethoxy - 1,4,4a,5,6,11b - hexahydro - 11H-benzo(a)carbazol-5-one.
8. 1,4,4a,5,6,11b - hexahydro - 11H - benzo(a)carbazol-5-one, hydrazone.
9. 4 - ethyl - 11 - benzyl - 1,4,4a,5,6,11b - hexahydro-11H-benzo(a)carbazol-5-one, hydrazone.
